UNITED STATES PATENT OFFICE

FRANCIS D. HARDESTY, OF PLEASANT RIDGE, MICHIGAN, ASSIGNOR TO HERRON-ZIMMERS MOLDING COMPANY, OF DETROIT, MICHIGAN, A CORPORATION OF MICHIGAN

TWO PART FINISHING MOLDING

Application filed June 29, 1929. Serial No. 374,902.

The present invention relates to finishing moldings especially for vehicle bodies and more particularly to moldings made in two parts, one of which is nailed or otherwise secured to the support and the other fixed over the nails or other securing means so as to provide a finished appearance.

Among the objects of the invention is a molding of the type indicated in which the 10 nailing strip is of novel form and permits a more easy securing in place of the finishing molding.

Other objects will readily occur to those skilled in the art upon reference to the following description and the accompanying drawings in which

Fig. 1 is a perspective view of a piece of the finishing molding.

Fig. 2 is a similar view of a piece of the 20 nailing strip.

Fig. 3 is a section showing the parts secured together and to a support.

Fig. 4 is a plan view showing the form of blank for the nailing strip, and

Fig. 5 is a plan view of a nailing strip 25 notched to permit easier bending.

As indicated in the drawing, the nailing strip is formed by punching a suitable blank as of the form shown in Fig. 4. This blank is 30 then placed in suitable dies and the side strips 10 brought together in the same horizontal plane while the cross strips 11 are bent up and formed to produce quadrilateral loops 12 either rectangular or diamond shaped, the 35 side strips being notched as at 13 and the nail holes 14 being provided at some time in the forming or punching operation.

The molding strip 15 is preferably of extruded metal and channeled as shown with 40 inwardly projecting ribs 16, providing recesses 17 behind them.

When the nailing strip has been secured to a support 20 as by nails 21 through holes 14, the molding strip 15 is applied with the apex 45 22 of the loop 12 centered in the channel, the latter being preferably grooved as at 23 along its center line. Pressure then applied to the molding strip causes the loop 12 to flatten and project its lateral apexes 24 into 50 the recesses 17 behind the ribs 16.

As indicated in Fig. 5, the side portions 10 of the nailing strip may be notched as at 13 to permit easier lateral bending of the nailing strip and the inner edges 30 of said strip may be welded or brazed or otherwise secured 55 together to aid the same operation.

Now, having described the invention and the preferred form of embodiment thereof, it is to be understood that the said invention is to be limited, not to the specific details herein described and illustrated, but only by the scope of the claims which follow:—

Claims:

1. An elongated two part finishing molding comprising an elongated channeled molding having laterally extending recesses in its inside walls and an elongated nailing strip comprising an elongated base provided with upstanding quadrilateral loops adapted to be flattened diagonally, whereby, when said molding is applied, the lateral corners of said loops become projected into said recesses to thereby fix the parts together. 65

2. An elongated two part finishing molding comprising an elongated channeled molding having laterally extending recesses in its inside walls and an elongated nailing strip comprising an elongated base provided with upstanding quadrilateral loops having one 70 diagonal substantially perpendicular to the plane of the base and being adapted to be flattened, whereby when said molding is applied, the lateral corners of said loops become projected into said recesses to thereby fix the parts together. 75

3. An elongated two part finishing molding comprising an elongated channeled molding having laterally extending recesses in its inside walls and an elongated nailing strip comprising an elongated base provided with upstanding loops adapted to be flattened, whereby when said molding is applied, the lateral portions of said loops become projected into 80 said recesses to thereby fix the parts together. 90

4. An elongated two part finishing molding comprising an elongated channeled molding having laterally extending recesses in its inside walls and an elongated nailing strip com- 95

prising an elongated base provided with up-standing spaced loops adapted to be flattened, whereby when said molding is applied, the lateral portions of said loops become projected into said recesses to thereby fix the parts together, said base being notched inwardly between said loops.

5. An elongated strip made entirely of thin flexible sheet metal and comprising a pair of elongated separated base portions having integral therewith and therebetween deformable quadrilateral cross loops, the base portions having evenly and longitudinally spaced nailings apertures of small diameter.
